UNITED STATES PATENT OFFICE.

WILLIAM ALONZO FORBES, OF BUTLER, OHIO.

DESIGN FOR A FASTENER FOR FENCE-STAYS.

SPECIFICATION forming part of Design No. 28,889, dated June 21, 1898.

Application filed December 20, 1897. Serial No. 662,757. Term of patent 14 years.

To all whom it may concern:

Be it known that I, WILLIAM ALONZO FORBES, a citizen of the United States, and a resident of Butler, in the county of Richland and State of Ohio, have invented and produced 5 a new and original Design for Fasteners for Fence-Stays; and I do hereby declare that the following is a full, clear, and exact description of the invention, which will enable others skilled in the art to which it appertains to 10 make and use the same, reference being had to the accompanying drawings, which form a part of this specification.

My invention relates to a new and useful 15 design for fasteners for securing the vertical stays to the horizontal strands of wire fences; and the leading feature consists in the peculiar configuration given to the fastener.

In the accompanying drawings, Figure 1 is 20 a perspective view of a fastener made in accordance with my design. Fig. 2 is a side elevation thereof. Fig. 3 is an elevation taken in plane at a right angle to that shown in Fig. 2. Fig. 4 is a bottom view.

In the said drawings the reference-numeral 25 1 designates a round piece of wire having one end bent upwardly and inclined outwardly at an angle to the vertical and longitudinal planes of the wire, forming an arm 2, and the extremity bent downwardly and inclined inwardly, forming a hook-like arm, at an angle to the arm 2. It will thus be seen that the arm 2 is bent outwardly at an angle to the portion 1 and also sidewise with respect to said portion. 30

Having thus fully described my invention, 35 what I claim is—

The design for a fastener for the stays of 40 wire fences, substantially as shown and described.

In testimony that I claim the foregoing as my own I have hereunto affixed my signature in presence of two witnesses.

WILLIAM ALONZO FORBES.
